UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PAPER REPLENISHING DEVICE FOR WEB PRESSES

Application filed March 20, 1922, Serial No. 545,225. Renewed December 8, 1931.

This invention relates to a device for automatically continuing the web supply to a web press when the supplying web roll becomes nearly exhausted.

The principal objects of the invention are to provide a practical automatic means for attaching the leading end of a new roll of paper to an expiring web without stopping, or slowing up, the press, even for an instant; to provide means for rotating the new roll at web speed which shall be separated from the means for rotating the old roll; to provide means for supporting the old and new rolls in such a manner that the new roll is connected with the web without changing the positions of either the new or old roll in the machine; to provide means for preventing all contact of the running web with the new roll before it is time to connect them together; to provide means for automatically operating the last named means to bring it out of its operative position and allow the web to contact with the new roll at the right instant to bring the web into contact with a pasted area of the new roll after the new roll has had an opportunity to speed up to web speed; to provide means connected with the contact preventing means and operable therewith for starting the new roll automatically without interfering with the operation of the press; to provide means connected with each new roll and located in a definite position with respect to the pasted area on its surface for controlling the operation of said contact preventing and rotating means; and to provide improved automatic means for severing the web from the exhausted roll.

Further objects and advantages of the invention will appear hereinafter.

Reference is to be had to the accompanying drawings, in which

Fig. 1 is an end view of a web replenishing device constructed in accordance with this invention, and showing the parts in the normal running positions when the web is nearly exhausted from the old roll;

Fig. 2 is an end view of the same;

Fig. 3 is a view similar to Fig. 1 on an enlarged scale, showing further details of the mechanism;

Fig. 4 is a sectional view of the new web roll and its core, showing the supporting means at one end in elevation;

Fig. 5 is a diagrammatic end view of the device, showing the parts in the position assumed in normal operation when the web is being taken from a fresh roll;

Fig. 6 is a portion of a similar view, showing the position assumed when the web is exhausted and the old roll is about to be severed after the parts have moved from the position shown in Fig. 1, and

Fig. 7 is an elevation of a new web roll, showing its pasted areas and the relative positions of the operating rollers therefor.

Many attempts have been made to provide speedier means than that usually employed for substituting a new web roll for an old one on web printing machines, particularly those which operate at high speed like newspaper printing machines. Usually they have been too complicated for practical construction and use. Also the printing press must be reduced in speed until at the moment of replenishment it is barely in motion and the affixing of the forward end of the new web to the rear end of the expiring web has had to be done mainly by hand. The web of the old roll has been severed on its core by hand while the motion of the other parts of the device had to be guided manually. These defects rendered the machines subject to uncertain operation on account of the manual control of certain features and did not materially increase the speed of printing because of the need of practically stopping the printing machines. The main object of these inventions has been to reduce the stoppage of the printing machine as much as possible.

As stated above, the present invention is designed for the purpose of effecting the change automatically and without need of hand manipulation and without any reduction in the speed or production of the press. All it requires is to be set by very simple action at any time before operation and then to start the machine. Then it will operate at a time determined by the position of the parts after the starting has been done by hand. It makes the substitution of the new paper sup-

ply for the old one while the press is running at full speed so that there is no reducing of the rate of production.

Referring to the drawings, the paper replenishing device is shown as located beneath a printing press, only a part of the frame 10 of which is shown in the drawings. The replenishing device is shown as supported on two pillars 11 resting on a foundation. Between these pillars is a shaft 12 on one end of which is located a worm gear 13 which meshes with a worm pinion 14 on the shaft of a motor 15. By means of this method of drive, the shaft 12 can be rotated and held firmly in any position in which it may be when the motor is stopped. This motor is intended to be operated intermittently as may be desired for the purpose of turning the shaft 12 one third of a revolution at a time.

20 The shaft can be turned by hand if desired.

Fixed on the shaft 12 between the pillars and adjacent to each of them are two spiders. Each of these spiders is made up of a hub 16 and three arms 17. In the end of each of the 25 spider arms is held a mandrel 20 by means of a screw 18 entering a slot 19 in the mandrel. The mandrels on one set of spider arms are opposite the mandrels on the corresponding spider arms. These mandrels are for securing in the space between them the paper rolls which are wound as usual upon cores 21 in the 30 form of pieces of pipe. The inner ends of the mandrels 20 are conical so that they may slip into the opposite ends of the cores 21. Upon 35 the extreme conical end of each mandrel is a fixed key 22 which fits into a key-way cut into the end of the core, as shown in Fig. 4. It will be obvious that when a roll of paper is placed between a pair of spider arms and the 40 respective mandrels are inserted into its core, the roller will be left suspended upon these mandrels. The rotation of the whole frame consisting of the six arms 17 by the motor 15 is the means used for raising and lowering 45 the heavy rolls of paper.

As there are three pairs of spider arms all similarly equipped, three rolls of paper may be carried at one time by this device. In 50 Fig. 5 I have designated the charging position C, replenishing position B and the running position A of the rolls. This may be considered the position of the paper roll carrying magazine at the beginning of the operation of the press.

55 Fig. 1 shows the situation after the roll A which is supplying the web W has been reduced down to a position in which it is time to connect the web with the second roll and continue the supply to the press from that roll.

60 The web runs from the expiring roll A on the arms 17 upwardly to a spring tension roller 25 which is carried between levers 26 pivoted on the base or frame 10 of the press. Springs 27 support the arms and the roller 25.

65 The web then passes to the left and up around

a stationary roll 28 to the printing press above. This description applies to both positions shown in Figs. 1 and 5 and, in fact, to all positions as the roll that is delivering to the press is always located in the position A 70 after it is once connected with the running web.

Two leather belts 30, engaging the roll A near its ends, run in the direction in which the web runs to the press at web speed for the purpose of assisting the rotation of the roll A which is feeding the web. Each endless belt 30 is suspended between two drums 31 and 32, the upper one of which is mounted on a shaft 33. This shaft is positively driven through a sprocket 34 mounted on the shaft, driven in turn by a chain 35 from a sprocket 36 operated by the press, the operation of which is not illustrated herein. In this manner, it will be seen that whenever the press 85 runs the belts also will run and the paper roll against which they contact will rotate at whatever speed the press is moving. So the web is always started from the feeding roll at the speed at which it is running in the 90 press irrespective of changes of speed of the press. This prevents sudden strains on the web and rupture thereof. Also, when the press stops the feeding roll will stop.

The drum 32 of each belt is suspended from the shaft 33 by an arm 37. These two arms carrying the drums 32 and their shaft are articulated about the shaft 33 and normally tend to hang downward on account of their weight. As the studs 20 on which the paper roll is mounted are located at a point almost directly under the center of the shaft 33 it will be seen that, whether the paper roll A is large or small, the belts will lie snugly its 100 surface in such manner that they can rotate it by their propelling action upon it.

There are three arms 38 articulated loosely about the shaft 33 above the replenishing roll B. One is located at each side of the replenishing roll and one between them so that they all extend over the surface of this roll. Through the outer ends of these arms runs a shaft on which there are fixed three rubber faced propelling rolls 39. This shaft is driven through a chain 29 from a sprocket 110 wheel on the shaft 33 and this sprocket is driven from the press as has been stated. It will be seen, therefore, that when the propelling rolls 39 are in contact with the upper paper roll B they will propel it at the surface 115 speed of the press in the same direction in which the paper is being drawn from the roll in Fig. 1.

It is to be observed that on the pillars 11 a pair of arms 41 are pivoted and provided with a convex shield 42. The arms 41 are articulated to a pair of links 40 extending upwardly which are connected to a rock shaft 43 through arms 44 fixed thereon. At the end 125 of the rock shaft 43 there is fastened an arm 130

45 which carries a stud 46 upon which is articulated a spring rod 47 carrying a strong spring 48. This rod slides in a bearing 49 on a bracket conveniently fixed on the press 5 frame and at its end it carries a buffer spring 50 for an obvious purpose.

At the same end of the rock shaft 43 is a cam shaft collar 55 fixed thereon having a trigger notch 51. In this notch lies a trigger 52 constituting the end of an arm 53 pivoted 10 on a bracket 54 fixed on the bottom of the press, if desired. The pressure of the spring 48 is exerted to turn the shaft 43 backwardly to the dotted line position shown in Fig. 3 15 but normally this is positively prevented by the trigger 52.

Swiveled on the rock shaft 43 is a hand lever 59 carrying a bolt 60 adapted to enter a drilled hole 61 in a collar 58 fixed on the 20 rock shaft. This bolt 60 is pressed by a spring 62 into locking position and is provided with a hand grip 63 for withdrawing it. It is by means of this that the rock shaft is turned to the full line position shown in Figs. 1 and 25 3 and cocked in that position against the action of the spring 48. From consideration of the parts so far described it will be obvious that the turning of the hand lever 59 from its horizontal position around to a lower position 30 in line with the axis of the notch 61 has turned the rock shaft to the position shown in Figs. 1 and 3. The handle is shown there as in the position to which it is brought after the hand grip is moved to disengage the bolt 35 from the notch 61 but under the action of the spring 48 the parts are left in this position with the shield holding the web away from the upper web roll.

It has been customary in machines for this 40 purpose to cover the forward or leading edge of the paper on the replenishing roll, in this case indicated at B, with paste as indicated at 64 in Fig. 7, except that in that figure I have shown the roll as having three areas 65 entirely free from paste. The rolls 39 are spaced as shown in Fig. 7 in the same relation as the clear spaces 65. This is to provide a free unpasted path for these rolls to travel over so that no paste will come into 45 contact with them. The points of the leading edge of the web on this roll are held to the roll by means of grease.

If it were not for the shield 42 the web 50 would come into contact with this web roll and with the pasted portion of it whenever the expiring roll became small enough. I provide in addition to this feature a cam 66 on each mandrel 20, at one end of the machine. On account of the fact that this 55 mandrel is secured to the paper roll through its key 22 it is clear that the mandrel will turn positively with the paper roll if that is rotated and thus the cam 66 will rotate in exact time with the paper roll. It is to be observed 60 that the cam 66, as shown in Fig. 5, corre-

sponds in radial position with the center of the position at which the pasted portions 64 are located on the circumference of the roll.

The lever 53 on which the trigger 52 is mounted is connected through a stud 67 with a vertical rod 68 which passes downwardly through an eye 69 carried by a horizontal push rod 70. This push rod 70 is carried by an extension 71 on one of the pillars 11 and a bracket 72 carried by a rod 73 which protrudes inwardly from the extension 71 of the pillar at that end. On the inner end of the rod 73 is articulated loosely a finger 74. The vertical plane of this finger 74 is the plane in which is located the cam 66. Therefore, as the roll revolves, the cam will raise the finger 74 once during each rotation.

The rod 68 which hangs from the trigger lever 53 is normally located at one side of the vertical plane in which the finger 74 moves up and down so that it will not be moved by it. But this rod 68 is free to swing sidewise slightly and can be so moved by the rod 70. This is moved to the left by pressing on a knob on its end against the action of the spring 75 which normally keeps it in inoperative position. It is plain that when this rod is pushed inwardly it will carry the end of the rod 68 into the path of the finger 74 and the next time said finger rises it will lift the trigger arm 53 and thus disengage the trigger 52 from the notch 51. Now, the spring 48 is free to operate and it moves the arm 45 over to the dotted line position in Fig. 3 and swings the rock shaft 43 with it. This raises the rod 40 and thus swings the shield 42 up into the dotted line position shown in Fig. 1. It is to be noted that this action is automatic and that it takes place in definite relation to the pasted spots 64 in their rotation. It may be stated here that the turning of the rock shaft 43 into the last named position brings the notch 61 into registration with the bolt 60 and the spring 62 thus forces the bolt into the notch. Now, after the web is pasted, the operator pulls down on the lever 59 and swings the rock shaft back to its original position so as to cock the shield in its dotted line position in Fig. 1. Then he raises the lever 59 to horizontal position again ready for the next operation.

The propelling rollers for the replenishing web roll B at the top of the machine have been mentioned and the way in which they are operated will not be described. The rock 120 shaft 43 carries at one end a lever 80 which has at its end a stud 82. This stud works in a slotted link 83 which is pivoted by a stud 84 at its lower end to one of the arms 38.

When the rock shaft 43 turns to the left from its cocked position, as above described, the stud 82 will bring up against the top of the slot in the lever 83 and raise this with the arm 38. This turns the shaft 33 and raises all three of the arms 38 and rubber rolls 39 so 125

that when the shield 42 is brought back to the dotted line position shown in Fig. 1 the rolls 39 will also be raised out of contact with the surface of the replenishing roll.

5 This having been accomplished, the mechanism is allowed to perform the motion of replenishment. When the time arrives the operator presses on the end of the rod 70. This moves the rod 68 over the finger 74 and 10 the next time the cam 66 comes around, that is, the next time the pasted spots 64 come into the position shown in Fig. 5, this will discharge the trigger mechanism and throw the shield from the position in full lines in 15 Fig. 1 to that shown in dotted lines, so as to let the paper web come firmly into contact with the surface of the upper web roll B, as shown in Fig. 6. It will be observed that this contact of the two webs cannot occur until 20 one of the pasted rolls is in such position that there shall have been established a firm contact of the two webs before the paste of one web shall affix it to the surface of the other. This is regulated by the shield which keeps 25 the webs apart until the proper time. But the cam 66 determines the exact instant at which the contact is made and as the paste can be applied to the replenishing roll at a point that may always bear a definite relation 30 to the position of the cam, the latter can be capable of insuring that the operation of pasting shall occur at the proper instant.

The severing of the web is performed by a blade 90 carried by a lever 91 having a heavy 35 counter-weight 92 on the other end to hold the blade up. It is held way down out of the way by a headed spring pin 95 slanted on one side so as to act automatically to hold up the arm having the weight, after it has once swung 40 above it as shown in Fig. 1 in dotted lines. A rod 93 guided in a guide 94 normally moves down to engage this lever and holds the serrated blade 90 in an intermediate position but away from the nearly exhausted roll when 45 the shield 42 is down. The upper end of this rod is pivoted to the arm 41 and obviously it is raised when the shield moves up. Thus, when the trigger is released, the knife blade 90 comes up slowly into contact with the expiring web roll from its intermediate position and the expiring web will be severed 50 from the running web at this time immediately after pasting.

To summarize, the operation is as follows: 55 Starting with the parts in the position shown in dotted lines in Fig. 5, the web on the roll at A is allowed to run nearly out. Then the lever 59, with the bolt 60 in the hole 61, is turned down and the shield 42, propellers 39 60 and rod 93 are thus brought down and the trigger 52 cocked. This bolt 60 is then disengaged from the hole and the lever 59 raised to the position shown in Fig. 3. The reduction 65 of the roll A to near its exhaustion point soon brings the web W into contact with the

shield 42. The roll B is rotating at web speed at its surface. The operator presses on the end of the spring pin 95 to release the lever 91 and let the weight 92 raise the blade 90 until its arm engages the rod 93 which holds it in the intermediate position shown in Figs. 1 and 5. Either before or after this the operator presses on the end of the rod 70 and holds it in against its spring during practically a rotation of the roll B. At the proper time during that rotation the cam 66 releases the trigger 52. The spring 48 turns the rock shaft 43 to the dotted line position in Fig. 3 and the arms 44, 45 and 80 turn with it. They raise the shield 42 and the propelling rollers 39 and allow the weight to raise the severing blade 90 to the position shown in Fig. 6. Thus the pasting is done, and the old web severed. The old web core is removed at A. Now the motor 15 is started and the magazine turned a third of a revolution. The lever 91 is turned up by hand to move the severing blade 90 down out of the way. It is moved far enough for the lever to snap over the bevelled end of the spring pin 95 which holds the blade in its lowermost position. When the new roll gets to the position B the old roll mandrels are in the position C ready to receive a new roll.

It will be seen, therefore, that these operations are entirely automatic, while the machine is set by hand by turning the lever 59, that could be done at any convenient time during the operation of the new roll, but is not done until the old web becomes nearly exhausted because otherwise it would keep the new roll rotating unnecessarily. The only thing required to start the machine is to touch the button constituting the end of the rod 70 and push it in. This, however, does not by itself determine the exact instant of pasting but merely determines during which rotation of the web roll B it shall take place. The exact instant of operation is determined by the cams 66. The press all the time runs at full speed without any reduction at all and without the need of any further manipulation. The severing blade, of course, is released and set in position ready to operate by pushing in the pin 95 as stated.

Although I have illustrated and described only a single form of the invention I am aware of the fact that modifications can be made therein by any person skilled in the art without departing from the scope of the invention as set forth in the claims. Therefore, I do not wish to be limited to all the details of construction herein shown and described, but what I do claim is:—

1. In a web replenishing device for a web press, the combination of means for supporting two web rolls, a series of friction surfaced propeller rollers, means operated from said shaft for rotating said rollers, a trigger mechanism normally holding said rollers

70

away from the new web roll, means for moving said rollers into and out of contact with the new web roll for rotating it, and means controlled by the angular position of said new roll for disconnecting the trigger mechanism when the new web roll is at a definite point in its rotation.

2. In a web replenishing device for a printing press, the combination of means for supporting an old roll and a new roll, means for guiding the web from an old roll to the press along a path adjacent to the surface of the new roll but out of contact therewith when the old roll is at its maximum size, both of said rolls being held in stationary position at this time, the path of the web being such as to approach the circumference of the new roll when the old roll is reduced to minimum size and remains in the position in which it was when of maximum size and supplying this web to the press.

3. In a web replenishing device for a web press, the combination of means for supporting two web rolls, a series of swinging arms, friction surfaced propeller rollers on said arms, means operated from said shaft for rotating said rollers, a trigger mechanism normally holding said swinging arms away from the new web roll, means for moving said rollers into and out of contact with the new web roll for rotating it, and means controlled by the angular position of said new roll for disconnecting the trigger mechanism automatically when the new web roll is at a definite point in its rotation.

4. In a web replenishing device for a printing press, the combination of means for supporting an old roll and a new roll, the new roll being in stationary position, means for guiding the web from the old roll to the press along a path adjacent to the surface of the new roll but out of contact therewith when the old roll is at its maximum size, the path of the web being such as to approach the circumference of the new roll when the old roll is reduced to minimum size and the new roll remains in its original position, and means for guiding the web to keep it out of contact with the new roll a part of the time.

5. In a web replenishing device for a printing press, the combination of means for supporting an old roll and a new roll, means for guiding the web from the old roll to the press along a path adjacent to the surface of the new roll but out of contact therewith when the old roll is of its maximum size, the path of the web being such as to normally intersect the circumference of the new roll when the old roll is reduced to minimum size and remains in the position in which it was when of maximum size and supplying its web to the press, and means for guiding the web to keep it out of contact with the new roll.

6. In a web replenishing device for a print-

ing press, the combination of means for supporting an old roll and a new roll, means for guiding the web from the old roll adjacent to the new roll but out of contact therewith when the old roll is of its maximum size, the new roll being located in position to normally touch the web when the old roll is nearly exhausted, a guide for guiding the web to keep it out of contact with the new roll, and automatic means for removing said guide out of the way when it is desired to attach the new roll to the old web, so as to let the web touch the new roll.

7. In a web replenishing device for a printing press, the combination of means for supporting an old roll and a new roll, means for guiding the web from the old roll adjacent to the new roll but out of contact therewith when the old roll is of its maximum size, the path of the web being such as to normally intersect the circumference of the new roll when the old roll is reduced to minimum size, and means separate from the rolls for keeping the web out of contact with the new roll, the last named means being movable to inoperative position to permit the running web to be applied and pasted to the surface of the new roll.

8. In a web replenishing device for a printing press, the combination of means for supporting an old roll and a new roll, means for guiding the web from the old roll adjacent to the new roll but out of contact therewith when the old roll is of its maximum size, the path of the web being such as to normally intersect the circumference of the new roll when the old roll is reduced to minimum size, and means for shielding the web from contact with the new roll, said shielding means being movable to inoperative position to permit the running web to be applied and pasted to the surface of the new roll, while the old roll remains supported in the position which it has occupied while the old roll was running out.

9. In a web replenishing device for a printing press, the combination of means for supporting an old roll and a new roll, means for guiding the web from the old roll in a path such as to normally intersect the circumference of the new roll when the old roll is reduced to a minimum size, web guiding means movable to inoperative position to permit the running web to be applied and pasted to the surface of the new roll while the old roll remains supported in the position which it has occupied while the old roll was running out, and means for thereafter moving the rolls to new positions in which the roll just attached to the web occupies the position normally occupied by the exhausted roll.

10. In a web replenishing device for a printing press, the combination of means for supporting an old roll and a new roll, means for guiding the web from the old roll in a

path normally intersecting the circumference on the new roll when the old roll is reduced to minimum size, means for keeping the web out of contact with the new roll comprising a shield, a cam mounted to rotate with the new roll, and means operated by said cam for automatically moving the shield out of the way.

11. In a web replenishing device for a printing press, the combination of means for supporting an old roll and a new roll, means for guiding the web from the old roll in a path normally intersecting the circumference of the new roll when the old roll is reduced to minimum size, means for keeping the web out of contact with the new roll, said means comprising a shield pivoted on the axis of said new roll, a cam mounted to rotate with the new roll and projecting from the center 20 in a direction toward a spot of paste on the circumference of the new roll, and means operated by said cam for automatically moving the shield out of the way when the pasted surface of the new roll comes into registration with the web:

12. In a web deplenishing device for a printing press or the like, the combination with means for supporting the expiring web roll and the new web roll, and in such relative positions that the web from the nearly exhausted roll will normally engage with the surface of the new roll, a shield adjacent to said surface interposed in position to hold the web out of contact with the new roll, means for moving said shield out of position.

13. In a web replenishing device for a printing press or the like, the combination with means for supporting the expiring web roll and the new web roll in fixed position, and in such relative positions that the web from the nearly exhausted roll will normally engage with the surface of the new roll, a shield adjacent to said surface interposed in position to hold the web out of contact with the new roll, means for automatically moving said shield out of position, and means connected with the shield and operated therewith for starting the new roll automatically into rotation and rotating it at web speed.

14. In a web replenishing device for a printing press, or the like, the combination with means for supporting the expiring web roll and the new web roll, and in such position that the web from the nearly exhausted roll will normally engage with the surface of the new roll, a movable shield adjacent to said surface interposed in position to hold the web out of contact with the new roll, a rock shaft, a series of positively rotating propelling rollers adapted to contact with the new roll to rotate it on its axis, and means connected with said rock shaft for moving said propelling rollers into contact with the new roll when the shield is moved into operative position.

15. The combination with a web press, of means for supporting a new web roll and running web roll in such position that when the running web roll becomes nearly exhausted the web therefrom will normally contact with the surface of the new roll, a shield pivoted on the axis on which the old roll is located, and manually operated means for moving said shield into a position to hold the web away from the new roll.

16. The combination with a web press, of means for supporting a new web roll and running web roll in such position that when the running web roll becomes nearly exhausted the web therefrom to the press will normally contact with the surface of the new roll, a pivoted shield, a rock shaft, means connected with the rock shaft for swinging the shield into position to hold the web away from the new roll and a hand lever mounted to swing on the axis of said rock shaft and having means for turning the rock shaft with it.

17. The combination with a web press, of means for supporting a new web roll and running web roll in such position that the web from the running roll will normally contact with the surface of the new roll, a shield pivoted on the axis on which the old roll is located, a rock shaft, means connected with the rock shaft for swinging the shield into position to keep the web out of contact with said new roll, a hand lever mounted to swing on the axis of said rock shaft, a hand grip on the lever adapted to detach said lever from the rock shaft whereby the lever can be swung to operate the shield and then moved back to normal position, and yielding means for automatically connecting the handle positively with the rock shaft whenever the rock shaft moves again to its original position.

18. The combination with a web press, of means for supporting a new web roll and a running web roll in such position that when the running web roll becomes nearly exhausted the web therefrom will normally contact with the surface of the new roll, a movable shield, manually operated means for moving said shield into a position to hold the web away from the new roll, means whereby said manually operated means can be automatically detached from the rock shaft, and an automatic trigger for holding the rock shaft in a position in which the shield is in engagement with the web.

19. The combination with a web press, of means for supporting a new web roll and running web roll in such position that the web from the running web roll will normally contact with the surface of the new roll, a movable shield, manually operated means for moving said shield into a position to hold the web away from the new roll, means whereby said hand operating means can be automatically detached from the rock shaft, an automatic trigger for holding the rock shaft

in a position in which the shield is in engagement with the web, and yielding means constantly acting on the rock shaft tending to move it into a position to withdraw the shield from operative position, said trigger constituting positive means for preventing the yielding means from acting.

20. The combination with the web press, of means for supporting a new web roll and running web roll in such position that the web from the running web roll will normally contact with the surface of the new roll, a movable shield, means for moving said shield into a position to hold the web away from the new roll, an automatic trigger for holding the shield in engagement with the web, yielding means tending to withdraw the shield from operative position, said trigger constituting positive means for preventing the yielding means from acting, and means adapted to be operated at a definite time in the rotation of the new roll for disengaging said trigger and allowing the yielding means to act.

25. 21. The combination with the web press, of means for supporting a new web roll and running web roll, a shield, a rock shaft for moving said shield into a position to hold the web away from the new roll, means connected with said rock shaft and movable into operative position when the shield is moved into operative position for rotating the new roll at web speed, an automatic trigger for holding the rock shaft in a position in which the shield is in engagement with the web, yielding means constantly acting on the rock shaft tending to move it into a position to withdraw the shield from operative position, said trigger constituting positive means for preventing the yielding means from acting, and means adapted to be operated at a definite time in the rotation of the new roll for disengaging said trigger and allowing the yielding means to act.

45. 22. The combination with a web press, of means for supporting a new web roll and running web roll in such position that when the running web roll becomes nearly exhausted the web therefrom will normally contact with the surface of the new roll, a shield pivoted on the axis on which the old roll is located, manually operated means for moving said shield into a position to hold the web away from the new roll, and means adapted to be operated when the shield moves out of operative position for severing the old web.

60. 23. In a web replenishing device for a printing press, the combination of means for supporting the old and new rolls in a definite position, means for guiding the web from the old roll out of contact with the surface of the new roll, means for severing the web from the old roll, and means for rotating the new roll at web speed, with a rock shaft, connections from the rock shaft for controlling the

operation of the last three means, means for holding the rock shaft in a position to prevent the operation of the severing means and to hold the new roll propelling means and guiding means in operative position, a push rod, a cam mounted in certain definite relationship with respect to the old roll and rotating therewith, a lever in the path of said cam adapted to be operated thereby once during each rotation of the old roll, and means connected with said push rod and adapted to be moved thereby into position to be engaged by the cam operated lever for disengaging said rock shaft holding means and thereby causing the guiding means and the propelling means to move out of operative position and allowing the severing means to move into operative position.

24. In a web replenishing device for a printing press, the combination of means for supporting the old and new rolls, means for guiding the web from the old roll out of contact with the surface of the new roll, means for severing the web from the old roll, and means for rotating the new roll at web speed, with a rock shaft, connections from the rock shaft for controlling the operation of the last three means, a trigger for holding the rock shaft in one position, a cam mounted in certain definite relationship with the old roll and rotating therewith, trigger operating means in the path of said cam adapted to be operated thereby once during each rotation of the old roll, and means adapted to be moved into position to be engaged by the cam operated for disengaging said trigger and thereby allowing the guiding means and the propelling means to move out of operative position, and the severing means to move into operative position.

25. In a web replenishing device for a printing press, the combination of means for supporting the old and new rolls, means for guiding the web from the old roll out of contact with the surface of the new roll, and means for rotating the new roll at web speed, with a rock shaft, connections from the rock shaft for controlling the operation of the last two of said means, a trigger for holding the rock shaft in one position, a cam mounted in certain definite relationship with the old roll and rotating therewith, trigger operating means in the path of said cam adapted to be operated thereby once during each rotation of the old roll, and means adapted to be moved into position to be engaged by the cam operated means for disengaging said trigger and thereby allowing the guiding means and the propelling means to move out of operative position.

26. In a web replenishing device for a printing press, the combination of means for supporting the old and new rolls in a definite position, means for guiding the web from the old roll out of contact with the surface of the

new roll, a rock shaft, connections from the rock shaft for controlling the operation of the last of said means, means for holding the rock shaft in a position to hold the guiding means 5 in operative position, a push rod, a cam mounted in certain definite relationship with respect to the old roll and rotating therewith, a lever in the path of said cam adapted to be operated thereby once during each rotation 10 of the old roll, and means connected with said push rod and adapted to be moved thereby into position to be engaged by the cam operated lever for disengaging said rock shaft holding means and thereby causing the guiding 15 means to move out of operative position.

27. In a web replenishing device, the combination with means for supporting a running web roll and a fresh roll and means for guiding the web from the running roll to a 20 press, of an operating means, means adapted to be set into operation by the operating means for rotating the fresh roll, a shield movable by the operation of the lever into position to prevent the web from the running 25 roll contacting with the surface of the fresh roll, means for severing the web from the running roll, means adapted to be set by the operation of said operating means for holding the severing means in inoperative position, means for stopping the fresh roll rotating means, removing the shield, and releasing the severing means, means rotatable with the 30 fresh roll for starting all of the last three mentioned means at a definite point in the rotation of the fresh roll, and manually controlled means for connecting said rotatable means with said three means.

28. In a web replenishing device, the combination with means for supporting a running web roll and a fresh roll and means for guiding the web from the running roll to a press, of an operating means, means adapted to be set into operation by the operating 40 means for rotating the fresh roll, means for severing the web from the running roll, means adapted to be set by the operation of said operating means for holding the severing means in inoperative position, means for stopping the fresh roll rotating means and 45 releasing the severing means, means rotatable with the fresh roll for starting the last two mentioned means at a definite point in the rotation of the fresh roll, and manually controlled means for connecting said rotatable 50 means with said two means.

29. In a web replenishing device, the combination with means for supporting a running web roll and a fresh roll and means for guiding the web from the running roll to a 60 press, of an operating means, a shield movable by the operation of the operating means into position to prevent the web from the running roll contacting with the surface of the 65 fresh roll, means for severing the web from the running roll, means adapted to be set by

the operation of said operating means for holding the severing means in inoperative position, means for removing the shield and releasing the severing means, means rotatable with the fresh roll for starting the last two 70 mentioned means at a definite point in the rotation of the fresh roll, and manually controlled means for connecting said rotatable means with said two means.

30. In a web replenishing device, the combination with means for supporting a running web roll and a fresh roll and means for guiding the web from the running roll to a press, of an operating means, means adapted to be set into operation by the operating 75 means for rotating the fresh roll, a shield movable by the operation of the lever into position to prevent the web from the running roll contacting with the surface of the fresh roll, means for severing the web from the running roll, and means adapted to be set by the operation of said operating means for holding the severing means in inoperative 80 position.

31. In a web replenishing device, the combination with means for supporting a running web roll and a fresh roll and means for guiding the web from the running roll to a press, of an operating means, means adapted to be set into operation by the operating means for rotating the fresh roll, means for severing the web from the running roll, and means adapted to be set by the operation of said operating means for holding the severing means in inoperative 90 position.

32. In a web replenishing device, the combination with means for supporting a running web roll and a fresh roll and means for guiding the web from the running roll to a press, of an operating means, a shield movable by the operation of the operating means into position to prevent the web from the running roll contacting with the surface of the fresh roll, means for severing the web from the running roll, and means adapted to be set by the operation of said operating means for holding the severing means in inoperative 105 position.

33. In an apparatus of the character described the combination of a rotatable magazine reel adapted to carry a plurality of rolls of paper, a normally inactive but press-driven means adapted to drive a fresh roll of paper to rotate the same and bring it to web-speed and means for rotating the reel to 115 effect contact of the fresh roll with the traveling web from the expiring roll.

34. In an apparatus of the character described the combination of a rotatable magazine reel adapted to carry a plurality of rolls of paper, rolls of paper mounted thereon, a normally inactive but press-driven means adapted to drive a fresh roll of paper having adhesive applied to the outer end thereof to rotate the same and bring it to web-speed, and 125 130

- means for rotating the reel to effect the contact of the fresh roll with the traveling web from the expiring roll and make a paster thereto.
- 5 35. In an apparatus of the character described the combination of a rotatable magazine reel adapted to carry a plurality of rolls of paper, a normally inactive driving means adapted to drive a fresh roll of paper to 70 rotate the same and bring it to web-speed and means for rotating the reel to effect contact of the fresh roll with the traveling web from the expiring roll.
- 10 36. In an apparatus of the character described the combination of a rotatable magazine reel adapted to carry a plurality of rolls of paper, a normally inactive driving means adapted to drive a fresh roll of paper to rotate the same and bring it to web-speed preliminary to making a paster, and means for rotating the reel to effect contact of the rapidly 75 rotating fresh roll with the traveling web from the expiring roll.
- 15 37. In a roll changer for printing presses, a fresh roll and an expiring roll, and means for changing the web feed from the expiring roll to the fresh roll, means for starting and driving the fresh roll, and separate and independent means for stopping the roll as it expires.
- 20 38. In a roll changer, the combination of a support for rotatably supporting a roll, means on each side of the support for frictionally engaging the roll, and means for rotating the support to bring the roll out of the control of one of the friction means and into the control of the other friction means.
- 25 39. In an apparatus of the character described, the combination of a rotatable magazine reel adapted to carry a plurality of rolls of paper, a normally inactive but press-driven means adapted to drive a fresh roll of paper to rotate the same and bring it to web-speed and means for effecting contact of the fresh 30 roll and the traveling web from the expiring roll.
- 40 40. In an apparatus of the character described, the combination of a rotatable magazine reel adapted to carry a plurality of rolls of paper, rolls of paper mounted thereon, a normally inactive but press-driven means adapted to drive a fresh roll of paper having adhesive applied to the outer end thereof to rotate the same and bring it to web-speed, and means for effecting the contact of fresh roll 45 with the traveling web from the expiring roll to make a paster thereto.
- 45 41. In an apparatus of the character described, the combination of a rotatable magazine reel adapted to carry a plurality of rolls of paper, a normally inactive driving means adapted to drive a fresh roll of paper to rotate the same and bring it to web-speed, and means for effecting contact of the fresh roll and the 50 traveling web from the expiring roll.
- 55 42. In an apparatus of the character described, the combination of a rotatable magazine reel adapted to carry a plurality of rolls of paper, a normally inactive driving means adapted to be brought in contact with a fresh roll of paper to rotate the same and bring it to web-speed preliminary to making a paster, and means for effecting contact of the rapidly 60 rotating fresh roll with the traveling web from the expiring roll.
- 60 43. In an apparatus of the character described, the combination of a rotatable magazine reel adapted to carry a plurality of rolls of paper, a normally inactive but press driven means adapted to rotate a fresh roll of paper and bring it to web speed and means for rotating the reel to effect contact of the fresh roll with the traveling web of the expiring roll.
- 65 44. In an apparatus of the character described, the combination of a rotatable magazine reel adapted to carry a plurality of rolls of paper, a press-driven traveling belt adapted to rest against the active roll and control the rotation thereof, a normally inactive driving means, also press-driven, adapted to drive a fresh roll of paper to bring it to web speed preliminary to making a paster, and means for rotating the reel to effect contact of the fresh roll with the traveling web to press the latter against the belt to assist in effecting 70 adhesion of the new web to the old.
- 70 45. In an apparatus of the character described, the combination of a rotatable magazine reel adapted to carry a plurality of rolls of paper, rolls of paper mounted thereon, a press-driven belt adapted to rest against the active roll and control the rotation thereof, a normally inactive but press-driven driving means adapted to drive a fresh roll of paper having adhesive applied to the outer end thereof to bring it to web speed, and means for rotating the reel to effect the contact of the fresh roll with the traveling web and press the latter against the belt to assist in securing adhesion of the 75 web of the fresh roll to the expiring web.
- 75 46. In an apparatus of the character described, the combination of a rotatable magazine reel adapted to carry a plurality of rolls of paper, rolls of paper mounted thereon, a normally inactive but press-driven driving means, means by which said driving means may drive a fresh roll of paper, having adhesive applied to the outer end thereof, to bring it to web speed, and means for rotating the reel to produce a paster of the new web to the traveling web from the expiring roll.
- 80 47. In an apparatus of the character described, the combination of a rotatable magazine reel adapted to carry a plurality of rolls of paper, rolls of paper mounted thereon, a press-driven belt adapted to rest against the active roll and control the rotation thereof, a normally inactive but press-driven means 85

adapted to drive a fresh roll of paper having adhesive applied to the outer end thereof to bring it to web speed, and means for rotating the reel to effect contact of the fresh roll with the traveling web and press the same against the press driven belt to aid in making a paster of the new web upon the expiring web.

48. In an apparatus of the character described, the combination of a rotatable magazine reel adapted to carry a plurality of rolls of paper, controlling means adapted to press against the active roll and control the rotation thereof, a normally inactive driving means adapted to drive a fresh roll of paper to bring it to web speed preliminary to making a paster, and means for rotating the reel to effect contact of the fresh roll with the traveling web, to press the latter against the controlling means to assist in effecting adhesion of the new web to the old.

49. In a web splicing device for a printing press, the combination with means for supporting a fresh web roll and a running roll, of feeding belts engaging the web on the surface of the running roll, means engaging the surface of the fresh roll for propelling it up to web speed, and means for moving the support for bringing the fresh roll out of contact with the propelling means and into contact with the feeding belts at the time of pasting, whereby the feeding belts perform the pasting operation.

In testimony whereof I have hereunto affixed my signature.

35 HENRY A. WISE WOOD.
